United States Patent

Des. 236,864
Patented Sept. 23, 1975

236,864

TOWEL BAR

Raymond U. H. Tegner, Lodi, Wis., assignor to Amerock Corporation, Rockford, Ill.

Original design application Jan. 4, 1974, Ser. No.
427,841. Divided and this application Sept. 3, 1974,
Ser. No. 502,622

Term of patent 14 years

Int. Cl. D6—06

U.S. Cl. D6—99

FIG. 1 is a front view of a towel bar incorporating my new design;

FIG. 2 is a bottom view of the towel bar.

FIG. 3 is an end view of the towel bar.

FIG. 4 is a fragmentary sectional view taken along the line 4—4 in FIG. 1.

This application is a division of my co-pending application Ser. No. 427,841, filed Jan. 4, 1974.

I claim:

The ornamental design for a towel bar, as shown.
